MOTOR VEHICLE DOOR LOCK ACCESSORY

Jules Haltenberger, Rancho Santa Fe, Calif.

Application January 31, 1950, Serial No. 141,519

2 Claims. (Cl. 70—455)

1

Automobile door locks, now in general use, include a fulcrumed door handle arranged to release the door upon operation of same. The front and trunk doors are usually provided with a co-operative rain protected key operated lock. In icing conditions (when rain freezes on surface) these locks proved to have a good performance, excepting however the trunk doors, when a somewhat upstanding lock and exposed face is without the provision of a rain protective lid.

Quite a few "named" automobiles now are provided with a cheaper lock construction. It consists of a stationary door handle, and an exposed operating plunger. The exposed plunger when on the front doors (or trunk door) is provided with a key operated exposed face lock, without the inclusion however, of a rain protecting lid.

The use of an exposed plunger and exposed face lock individually and collectively fail in icing conditions.

It is the object of my invention, to provide a quick mountable and quick demountable accessory cover for the automobiles now being delivered, arranged to protect the plunger per se and to protect the associated lock face when used, and in the preferred form to mount the cover substantially endwise to the plunger, further to permit the use of such accessory without any remachining operation or performance interference, and to arrange for the quick removal of same for warm weather, while leaving the present structure un-blemished.

A further object is, to provide as by a simple provision of a groove a hand insertable and hand removable rubber (or the like) thimble arranged to be used only when icing conditions are to be met, while at removal retaining a desired pleasing appearance.

Further objects will appear as the description proceeds.

Referring to the drawings: Fig. 1 is a plan view of a plunger operated lock and handle, with some accessory parts in section; Fig. 2 is side elevation of a part of Fig. 1; Fig. 3 is a section substantially on line 3—3 of Fig. 1; Fig. 4 is a section substantially on line 4—4 of Fig. 1, with parts left out; Fig. 5 is a schematic drawing of the lock; Fig. 6 is a modification of the invention shown as a production accessory; Fig. 7 is an accessory application of the invention for the usual rear doors of an automobile; Fig. 8 is a production accessory application for rear and trunk doors; Fig. 9 is a modification of the invention; Fig. 10 is an enlarged section of a part shown in Figs. 6, 8 and 9; Fig. 11 is decorative insert to be used after the

2

removal of the thimbles shown in Figs. 6, 8 and 9, here shown in a larger scale; Fig. 12 is the application of the invention on a usual T handle body front or trunk door lock, an accessory for a series of automobiles in use, here shown in a smaller scale; Fig. 13 is a side elevation of Fig. 12; Fig. 14 is a top view of the accessory shown in Figs. 12 and 13. Fig. 15 is a side elevation of a usual body front or trunk door handle and lock; Fig. 16 is a plan view of Fig. 15; Fig. 17 is a plan view of a door handle and lock with an access cover and mounting means shown partly in section; Fig. 18 is a side elevation of Fig. 17; Fig. 19 is a section substantially on line 19—19 of Fig. 17; Fig. 20 is a section substantially on line 20—20 of Fig. 17.

Referring to Figs. 1 to 5 inclusive, it will be seen that the rear part of a usual automobile door having a wall 10 is folded over and is arranged to seat on door ledge sealer 11 and door ledge 12 respectively. Wall 10 as by screws 13 support a stationary door handle, generally at 14. Handle 14 is formed into a handle hub 15 operatively supporting a free sliding cylindrical protruding lock release plunger 16, and it is yieldingly held in the illustrated extended position as by spring 17 and plunger travel guide and travel length limiter 18 operating in groove 20.

The lock structure now appearing in new automobiles as shown in Figs. 1, 2, 3, and schematically in Fig. 5, provides a spring loaded plunger 16 containing a usual spring loaded key operated lock structure having an exposed face 21 and a key hole 22 therein. The lock is provided with a longitudinal extension 23, terminating in a centrally off-set portion 24. Portion 24 is normally aligned with a spring loaded depending release lever 25, which is provided with a cam and engaging part 26, here shown, holding a spring loaded release bar 27 having an end roller 28 in door closing position. Plunger 16 and parts 21 to 28 inclusive are mounted on the movable door. The stationary door ledge 12 is provided with an upwardly curved groove 29 for the admission and upward guidance of roller 28.

In operation, when the door is hand closed, the roller 28 rolls upwardly, arcuately lifting bar 27, when a portion thereof reaches above the engaging part 26, part 26 engages the bar; the door remains closed. When the plunger is pressed, end of portion 24 contacting and moving lever 25, disengages part 26 from bar 27, releasing the lock; the door can be opened. With a key operation, part 24 is displaced from the path of depending part 25; the door becomes locked.

Hub portion 15 is provided with a decorative

curved portion 30, applicant uses this portion to support a cover here in the shape of a sealing thimble generally at 31. Thimble 31 is made of yielding rubber or other elastic material like yielding plastic, and is formed of a sealing circular flange 32, a smaller diameter forwardly extending plunger protective skirt 33 and lock face protecting apron 34. Apron 34 downwardly terminates at a material distance from the face of the plunger 16 in a bead 35 forming a beaded generally triangular opening 36.

Thimble 31 is removably held to the hub by a curved circular sealing plate 37 having a tongue portion 38 arranged in shape to conform to the outer portion of handle 14, where as by wrapping band 40 and tightening bolt 41 and nut 42 the sealing plate and thimble respectively are secured. The illustrated thimble protects the plunger and lock from icing conditions.

In operation, the yielding material thimble does allow the plunger to be displaced without interference, as only the outer half of the exposed plunger travel is used for the door opening. When it is desired to key lock or unlock the door, by lifting the apron (shown in Fig. 6) the key becomes insertable, operable and removable, while deforming without stretching the apron.

By the removal of band 40, the associated sealing plate and thimble can be facilely removed and stored for next winter. The here described accessory is inexpensive and it is mountable and demountable by the use of a mere screw-driver thereby forming quick removing means, it does not disfigure the automobile, and assures the lock successful operation for the rare but desperately needed occasions.

A different thimble mounting method is shown in Fig. 6, otherwise the thimble is as hereinabove described. Here a thimble at its base is formed into a larger diameter having in circular bead 43, disposed in groove 44, a groove provided by re-machining in the front end of hub 15'. In this mounting the sealing plate and wrapping band is eliminated. Fig. 6 also shows a usual key in inserted position, and a key lifted apron, giving key access while deforming, without stretching the apron.

The rear doors of an automobile are not provided for a key lock, for each of these applicant provides a quick removable end sealed cylindrical thimble.

Fig. 7 illustrates a thimble generally at 45 having a cylindrical skirt 46 and circular end 47 here shown as an accessory for automobiles now being delivered; the mounting method shown was described in connection with Figs. 1 to 4 inclusive. For simplicity of presentation the indicating numerals are duplicated. Thimble 45 protects the plunger in icing conditions, and does not interfere with the operation. It is summer removable.

Fig. 8 shows the thimble illustrated in Fig. 7; here however, the mounting method of thimble at 45' is provided with a bead as described in connection with Fig. 6. For simplicity of presentation the indicating numerals are duplicated.

When it is desired to provide a door release plunger with a decorative operable lid, this is illustrated in Fig. 9, here applicant provides for the thimble to protect the plunger and at the same time to serve as a sealing surface for an operable lid. As is clear from the drawing, plunger 16' is provided with a threaded opening for a fine threaded stud 50 a part of a rivet 51 permanently secured in lid 52. Thimble at 45' outwardly terminates in a bead 53, sealing the lid

when in closed position. Should the sealing rubber set and quit sealing, then turning the lid one or more turns will re-create a sealing surface. The thimble and lid both are hand removable for storage for the next winter icing conditions.

In Figs. 6, 8 and 9 it is the intent to insert and remove the thimble by hand operation, thereby forming a quick removing production accessory means. For clarification this is illustrated in Fig. 10 on a larger scale where bead 43 clearly shows a flattened surface 43'. This flattening allows the bead to pass between the outer edge of groove 44 and plunger 16. At insertion, the bead snaps in the groove for quick mounting, here the bead serves as the thimble mounting means.

After the removal of the thimble shown in Figs. 6, 8, 9 and 10 applicant provides a disc insert for a decorative purpose as shown in Fig. 11, in the access opening for groove 44 a usual ring plug having an outer wall 54 is turned over inwardly to terminate in hollow pilot cylinder 55. In this pilot three bulges 56 (only one is shown) removably hold the decorative disc in position. The disc is removed and the thimble is inserted for icing conditions.

Whereas it is the object to provide for protection of plunger operated locks now starting in production, most previous series of cars were produced with lid-less trunk door locks, then locks invariably failed in icing conditions. By applicant's own experience, cleaning, drying and graphite powdering failed to remedy this shortcoming. It is here proposed to used an apron shown in Figs. 1, 2, 3 and 6 and applied to a front door T handle or to the trunk door of the automobiles hereinabove referred to, this is shown in Figs. 12, 13 and 14. It will be seen, that a trunk or front door 58 operatively supports a usual older type front trunk T door handle having a hub 15'', wherein, a usual lock having an exposed protruding barrel 16'' with an exposed face 21' is operatively supported. Face 21' is provided with a usual key hold (shown in Fig. 2, here not shown). The hub is provided with two usual overhanging hand operating arms 60. Here face 21' is protected by an apron 34' with its bottom edge at a material distance from face 21' having side walls 61, the apron is integral with a supporting substantially diametrically enlarged rubber or equal yielding material bracket 62. This bracket is provided with a depending front snap arm 63 and two depending rear snap arms 64. This accessory hollow cover is snapped on the present day T handles, to serve as mounting means for the cover. For the key insertion the apron is lifted and deformed without stretching, in the manner described in connection with Figs. 1 to 6 inclusive. For quick mounting the accessory is simply pressed in place, the arms yielding, form a snap engagement, inversely, by lifting the snap arms the accessory is quickly removable.

Figs. 15 and 16 show a modification of the mounting described in connection with Figs. 12, 13 and 14. A rubber cover 62' is held by a U-shaped spring steel or plastic snap retainer 65 having a yielding depending front snap arm 63' and two rear arms 64', to serve as mounting means for the cover. To prevent the theft of the accessory the ends of arms 63' and 64' might be wire connected as shown by chain line 66.

When it is desired to snap engage the accessory on the door handle shown in Figs. 1, 2, 3 and 4, this is shown in Figs. 17, 18, 19 and 20. Here sealing plate 37' is provided with a tongue portion 38' terminating in bent portion 67 arranged to

form a contact with handle 14. The tongue is also provided with handle overlapping portions 63 terminating in snap hooks 70. To prevent theft of the accessory it might be wired as shown by chain line 71.

By mounting the accessory and pressing it in place, quick mounting means is arrived at by snap engagement. By separating the hooks quick removing means is secured.

Winterization is now an accepted procedure, the here proposed accessory is intended to be mounted before the arrival of icing condition and removed after the icing dangers are past. The here proposed simple method to free the motor vehicle from icing consequences is of great importance to physicians and surgeons, law enforcing agents, armed services, or in any emergency call, also on trucks and school busses and is of particular importance in the northern States and services in Alaska. Applicant believes the here proposed protection to be of genuine benefit to the public.

In the appended claims "rubber" shall mean rubber per se, or an other material like yielding plastic, having the general characteristics of rubber for the intended purpose.

It will be noted, that the depending apron in all figures where shown are alike, permitting key insertion without stretching the apron. All the aprons have relatively thin beads to permit key insertion to the demanded depth where the key enlarged head leaves but a small space between the lock face and head. To avoid bead stretching, therefore applicant positions the apron bottom at a material distance from the lock face.

It will also be noted that the exposed portion of the covers are duplicated in Figs. 1, 2, 3, 6, 17 and 18. And all covers provide for substantially lock endwise mounting for quick applicability.

It is important to note, that in my invention the key insertion is a simple quick and effortless apron lifting operation, that can be facilely performed by women or children either in light or in darkness. This invention permits the key insertion while wearing gloves or zero weather mittens as the gloved hands handle the key only.

In the appended claims, accessory shall mean an accessory cover which is intended to be applied in or near freezing weather.

While I have herein shown and described only certain specific embodiments of my invention and have suggested only certain possible modifications, it will be appreciated that many changes and variations can be made to suit particular conditions and embodiments of use, without departing from the spirit and scope of my invention. 55

What applicant claims as his invention:

1. An accessory for use on a motor vehicle door having a door handle with a handle hub and an endwise sliding cylindrical lock release plunger having an exposed operating end protruding outwardly from the hub, comprising a yieldable hollow thimble-shaped cover of rubber-like material substantially endwise fittable over and freely receiving the plunger operating end, and yieldable mounting means removably fittable on a portion 10 of the handle adjacent to the hub, to removably hold the cover on the hub, said yieldable hollow cover having on its outer end a depending hood-shaped apron adapted to be normally free of contact with the protruding end of the sliding operating plunger and terminating in a free edge which surrounds an opening in the under side of the cover through which a key may be inserted and moved to displace said apron to give access to a keyhole in a lock in said cylindrical plunger.
2. For use with an automobile door handle with handle hub having a cylindrical lock release operating plunger endwise slidable in the hub with an exposed operating end protruding outwardly from the hub, an article of manufacture comprising a yieldable hollow thimble-shaped cover of rubber-like material having an inner open end and shaped for freely receiving the protruding end of the sliding operating plunger 25 and means for securing said cover to the hub, the closed outer end of said cover being in the form of a depending hood-shaped apron adapted to be normally free of contact with the protruding end of the sliding operating plunger and terminating in a free edge which surrounds an opening in the under side of the cover through which a key may be inserted and moved to displace said apron to give access to the keyhole in the cylindrical lock when said article of manufacture is secured to 30 the hub.

JULES HALTENBERGER.
